UNITED STATES PATENT OFFICE.

GEORGE ELLIS SMOUSE, OF WASHINGTON, DISTRICT OF COLUMBIA.

TRUCK OR TRANSPORTING DEVICE.

Application filed February 27, 1926. Serial No. 91,093.

This invention relates to improvements in trucks or transporting devices and has particular reference to such trucks as are adapted for use in transporting type forms 5 from one table or support to another.

One object of the present invention is to provide simple and efficient means whereby the receiving or supporting member of the devices may readily be raised or lowered and 10 maintained in a position substantially parallel with the plane of the top of the frame or body of the truck.

With this and other objects in view, the invention consists in certain novel features 15 of construction and combinations of parts as hereinafter set forth and pointed out in the claims.

In the accompanying drawings;

Figure 1 is a view in elevation of a truck 20 or carrier illustrating an embodiment of my invention, and showing the vertically movable table or platform in its raised position;

Figure 2 is a vertical sectional view (part- 25 ly broken away) showing positions assumed by the parts when the table or platform is in lowered position;

Figure 3 is a plan view, the table or plat- 30 form being removed;

Figures 4 and 5 are enlarged views showing certain details, and

Figure 6 is a view of a modification.

The frame or body of the truck may comprise upper and lower side bars 1, 2, end 35 bars 3, 3 and uprights 4. The side and end bars 1-3 may be united by permanent corner couplings 5, and with these couplings, the legs or upright 4 are connected; said legs or uprights being also connected with 40 the lower side bars 2, through the medium of couplings 6. Suitable castors 7 may be provided at the lower ends of the legs or uprights 4.

Brackets 8 are located on the side bars 1 45 adjacent respective ends thereof and provide mountings for the end portions of transverse shafts or bars 9, 9. On these shafts, the end portions of the parallel arms of bail levers 10 are mounted and said bail 50 lever arms may be secured by means of set screws 11. Levers 12 are also mounted between their ends on the shafts 9 adjacent the connection of the bail lever arms thereto and may be secured to said shafts by set screws 55 13. The levers 12 are provided each with a finger 14 and these fingers may be pro-

vided with rollers 14^a to engage lugs or feet 15 which depend from a table or platform 16 disposed over the frame or body of the truck. Each of these feet or legs may be 60 provided with a plate 17 to be directly engaged by the rollers of lever fingers 14. These plates may be held in place by dowels 18 and one or more washers 19 may be placed between said plates and the lower ends of 65 the feet or legs 15 to effect adjustment of the length of the latter. Each of the levers 12 is also provided with a toe 20 below the mounting of the lever on shaft 9, and the toes 20 project laterally so that their free 70 end portions will be disposed under the parallel arms of the bail lever, in proximity to the connection of said arms with the shaft 9. Screws 21 provided with lock nuts 22, 75 pass through the toes 20 and engage the adjacent bail lever arms. In this manner, there is provided an adjustable operative connection between the bail levers and the levers 12 for causing the latter to effect the raising or lowering of the table or platform 80 when the bail levers are operated.

In order to insure proper operation of the levers to effect the even vertical movements of the table or platform 16, I provide link connections between the two bail 85 levers 10, 10. In the embodiment of the invention shown in Figures 1 to 4 inclusive, the adjacent arms of the respective levers 10 (near each side of the truck) are connected by pivoted links 23, 24, these links being 90 pivotally connected at their outer ends with arms of the respective levers 10, and mounted at their inner ends on a bolt 25. The boss 26 on the link 23 is freely mounted on the bolt, but the boss 27 on the link 24 may be interiorly threaded to engage a threaded portion 28 on the bolt. A nut 29 is provided on one end of the bolt 25 and, near the other end of said bolt, a collar or head 95 30 may be located to provide an abutment for the boss 26, while a spacer 31 may be disposed between the two bosses 26 and 27. Each bolt 25 extends at one end beyond the collar or head 30, and has mounted thereon, a roller 32. The rollers 32 on the respective 100 bolts 25 ride in vertical guideways provided by channel irons 33, each secured at its upper end to an upper side bar 1 of the frame and at its lower end to a lower side bar 2 of the frame, and said vertical guideways 105 or channel irons are located midway between the ends of the frame. Each bolt 25 110

may be formed at the end on which the roller is mounted, to receive a screw-driver or other tool, and the adjacent channel iron 33 may be provided with an opening 33^a to facilitate the application of the tool to the bolt.

In the embodiment of the invention shown in Figure 6, a single link 34 is employed between each pair of adjacent arms of the 10 respective levers. To facilitate the attachment of such link, brackets 35, 35 are secured to adjacent arms of respective levers 10 and provided with lugs 36 to which respective ends of the link 34 are connected. 15 It is desirable that means be provided to restrain the descent of the table or platform 16, and for this purpose, braking devices may be employed, and in the drawings is shown one embodiment of such braking devices. Brake wheels 37 are secured (preferably by set screws 37^a) to the respective shafts 9 and a brake band 38 extends from one of these brake wheels to the other. The 20 end portions of the brake band embrace the respective brake wheels, and to the extremities of said band, rods 39 are connected and pass through holes in the band, said rods being threaded to receive nuts 40, between which latter and the band, springs 41 are located.

Having fully described my invention what I claim as new and desire to secure by Letters-Patent, is:—

1. In a transporting device of the character described, the combination with a truck frame and a vertically movable table, of 25 levers mounted in said frame, lever members fulcrumed coincidently with said levers and cooperable with said levers and with the table to effect raising or lowering of the latter, and means to adjust the relation of said lever members relatively to the levers and the table.

2. In a transporting device of the character described, the combination with a truck frame and a vertically movable table, of two lever structures supported by the truck frame and cooperable with the table to effect raising and lowering of the same, and floating 50 pivoted link devices connecting the two lever structures with each other midway the ends thereof.

3. In a transporting device of the character described, the combination with a truck 55 frame and a vertically movable table, of two

lever structures supported by the truck frame and cooperable with the table to effect raising and lowering of the same, pivoted link devices connecting the two lever structures with each other, rollers carried by said link 60 devices, and vertical guides for said rollers secured to the truck frame.

4. In transporting devices of the character described, the combination with a truck frame and a vertically movable table, of two 65 bail levers supported by said frame, operative connections between said levers and the table, pairs of pivotally connected links pivotally connected with arms of the respective bail levers, a roller connected with each pair 70 of pivoted links in line with the pivotal connection between the links, and vertical guides secured to the frame for the rollers.

5. In a transporting device of the character described, the combination with a truck 75 frame and a vertically movable table, of two bail levers supported by said frame, lever members adjacent the arms of the bail levers and having toes projecting under the arms of the bail levers, a set screw passing through 80 each toe and cooperable with the adjacent bail lever arm, said lever members also having fingers cooperable with the table, and link connections between the respective bail levers.

6. In a transporting device of the character described, the combination with a truck frame and a vertically movable table, of two lever structures, lugs on the under side of the table, removable plates at the lower ends of 90 said lugs and carried thereby and positioned for cooperative relation with said lever structures, and floating link devices connecting the two lever structures between the ends thereof.

7. In a transporting device of the character described, the combination with a truck frame and a vertically movable table, of two bail levers supported by the truck frame, connections between said levers and the table, 100 two pairs of links, pivotal connections between the outer axes of the links of each pair and arms of the respective bail levers, a bolt connecting the inner ends of the links of each pair, rollers carried by the respective bolts, and vertical guides secured to the truck frame and receiving said rollers.

In testimony whereof, I have signed this specification.

GEORGE ELLIS SMOUSE.
